Primary Examiner — Nathaniel D. Buckner*(74) Attorney, Agent, or Firm* — Amster, Rothstein & Ebenstein LLP(57) **CLAIM**

We claim the ornamental design for a smart door lock, as shown and described.

DESCRIPTION

FIG. 1 is a front view of a smart door lock showing our new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The present product is used for locking a door.
